Primary Examiner — Christian P. McLean
Assistant Examiner — Nader Abadir(57) CLAIM

The ornamental design for a knife, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front right perspective view of a knife;
FIG. 2 is a front view of FIG. 1;
FIG. 3 is a rear view of FIG. 1;
FIG. 4 is a left view of FIG. 1;
FIG. 5 is a right view of FIG. 1;
FIG. 6 is a bottom front perspective view of a handle of the knife;
FIG. 7 is a front view of FIG. 6;
FIG. 8 is a rear view of FIG. 6;
FIG. 9 is a left view of FIG. 6; and,
FIG. 10 is a right view of FIG. 6.1 Claim, 10 Drawing Sheets
